Element-A, posted on elementalmachines.io, no posted date given, no production date given, [online], [site visited Mar. 30, 2018], Available from Internet, URL: <http://elementalmachines.io/products/elements/> (Year: 2018).*

Primary Examiner — Garth Rademaker*Assistant Examiner* — Fitzgerald L Butac(74) *Attorney, Agent, or Firm* — Larson & Anderson, LLC(57) **CLAIM**

The ornamental design for a sensor device, as shown and described.

DESCRIPTION

FIG. 1 is an isometric view of a sensor device showing the new design.

FIG. 2 is a top plan view thereof;

FIG. 3 is a bottom plan view thereof; and,

FIG. 4 is a left-side elevation view thereof; the right-side, front, and rear elevation views are identical.

The broken lines show portions of the sensor device that form no part of the claimed design.

1 Claim, 4 Drawing Sheets(56)
